AUTOMATIC LOADING AND DUMPING
WASHER

Jean Louis Boulade, Alturas, Calif.

Application November 25, 1935, Serial No. 51,492

12 Claims. (Cl. 68—18)

My invention relates to improvements in washers and particularly to that type of washer used in laundries and cleaning establishments, wherein a horizontally disposed perforated cylinder, split longitudinally and axially into upper and lower hingedly connected halves, operates in conjunction with upper and lower housings, movable vertically to enclose and uncover the upper and lower halves forming the cylinder, which 5 actuate mechanism, during such movements, to automatically invert the upper half of the cylinder to a loading position to receive the load for the next cleansing and to automatically move the lower half of said cylinder to a dumping position and to automatically return said lower half 10 to a receiving position and the upper half, with its replenished load, to normal matching position with the lower half to form said cylinder, thereby dumping the load from the upper half into the 15 lower half.

The primary object of the present invention is to provide a new and improved automatic loading and dumping washer to save the time and labor required for manual loading and unloading.

Another object is to provide a new and improved washer having improved means actuated by the opening and closing of a stationary housing, usually enclosing the rotatable cylindrical perforated washer, for automatically inverting 25 the top or lid of said cylinder to a loading or receiving position upon one side of the device and for automatically moving the bottom half or container to a dumping position upon the opposite side of the device, thereby permitting the loading and unloading operations to take place substantially simultaneously to effect a further saving of time.

A further object of the invention is to provide new and improved means for positively locking 40 the two halves of the rotatable cylinder together to prevent their opening or separation during the washing or cleansing period.

A still further object is to provide actuating means for inverting the lid, or upper half of the cylinder, to receiving or loading position and reverse, and the lower half to dumping or dispensing position and reverse, by means of mechanism which normally disengages said upper and lower halves and automatically engages said 45 halves to operate the same and automatically disengages said halves after the operation, whereby said rotating cylinder may be free to rotate when said housing is closed and the moving mechanism automatically disengaged.

A still further object is to provide means for

normally positioning the upper and lower halves to facilitate engaging relation of the operating mechanism therewith, when the rotating impulse has been removed from said rotating cylinder.

I accomplish these and other objects by means 5 of the improved device disclosed in the drawings forming a part of the present specification, and in which—

Fig. 1 is a broken side elevation, disclosing my improved washer, the central vertical lines being 10 used to indicate that the said washer may be of any suitable length;

Fig. 2 is an enlarged broken transverse sectional view taken on line 2—2 in Figs. 1 and 3 of the drawings in the direction indicated; 15

Fig. 3 is an enlarged broken view, partly in section, taken on line 3—3 of Fig. 2 of the drawings, disclosing one end of the perforated cylindrical washer in elevation and one end of the outer housing in section, and also disclosing the 20 parts in normal position to permit rotation of said washer;

Fig. 4 is a slightly reduced transverse sectional view disclosing the initial or first movement of the device; 25

Fig. 5 is a similar view disclosing the dumping and receiving positions; and

Fig. 6 is a detail view disclosing, in plan, the cradle which supports the cylindrical, rotating washer. 30

Referring to the drawings:

The numeral 1 is used to designate in general a suitable frame within which are rotatably mounted and supported the trunnions 2 mounted upon the upper surfaces of the opposite ends of an open rectangular cradle 3, said cradle being below the axis of the trunnions 2 so that the cradle 3 is rotatably suspended, the purpose of which will hereinafter be more fully set forth. One trunnion is provided with the usual triplicate pulleys 4 for rotating the cradle in opposite directions, according to present custom, while the other trunnion 2 is provided with a wheel 6 having an aperture 7 which registers with a similar aperture 8 within a bracket 9, mounted upon the frame 1, to receive a pin or other suitable device 11 to retain the cradle 3 in stationary suspended position during the loading and dumping operations, as disclosed in Fig. 1 of the drawings. 35 40 45

The perforated cylinder or washer comprises 50 what I designate throughout the specification and claims, for simplicity, a lower half 12 having one edge hingedly connected as at 16 to one side of the cradle 3 and its free edge resting upon the opposite side of said cradle, and an upper half 55

14 having one edge hingedly connected to said opposite side of the cradle 3 as at 17 and its free edge resting upon the first side of said cradle 3, the two halves thus being in matching relation to 5 form a cylindrical washer, as disclosed in Fig. 2 of the drawings.

The two halves 12 and 14 are held locked in matching relation, during their period of rotation, by means of a latch 18 pivotally mounted upon 10 the under side of the cradle 3 upon which the hinge 16 of the lower half 12 is located. This latch is preferably in the form of an inverted U and extends the length of the said halves and rests upon the flange or free edge of the upper 15 half 14. A rod 19 connects the latch 18 to an arm 21 pivotally mounted upon one end of the cradle 3 and provided with a slot 22. When the arm 21 is lowered, it closes the latch 18 upon the upper half 14 and thereby locks the upper and lower 20 halves 14 and 12 respectively, together, and to the cradle 3. The tension of a spring 23, connected to the cradle 3 and the arm 21, normally retains the latch 18 in locked or unlocked position by holding the connecting point of said rod 25 with said arm on either side of the pivotal center of said arm, in the well known manner.

While I have illustrated, in detail, only one end of the washer and its component operating mechanisms, it is to be understood that similar mechanism is applied to both ends of the device, the parts being right and left, and may be described as follows:

While the upper and lower halves 14 and 12 extend fully from side to side of the cradle 3, they 35 do not extend entirely to the ends of said cradle, but stop short of said ends, as indicated in dotted lines in Fig. 6 of the drawings, in order to provide a space between the ends of said upper and lower halves and the inside of the cradle 3 to permit the passage and operation of certain mechanisms.

A rigid arm 26 extends downwardly from each end of the upper half 14, beyond the end of the cradle 3, and to a point preferably below the center of the lower half 12 and has a slot 27 arranged 45 on a line slanting approximately 45 degrees from the hinge 17 of the upper half 14, as disclosed in Fig. 2 of the drawings.

A lever 28 is pivotally mounted upon the cradle 3 concentric with the hinge 17 of the upper half 14, one lower end of said lever substantially registering with the slot 27 of the arm 26, although the two have no connection. A suitable link 29 connects the free end of said lever 28 with the top 55 edge of the lower half 12. The opposite end of the lever 28 is slightly bent for a purpose herein-after more fully set forth, and is provided with a lateral flange 31 arranged to be engaged by the upper half 14 when moving to a loading position.

An upper housing 33 is mounted for vertical movement upon the frame 1 to enclose and uncover the upper half 14 by means of worms 34 at 60 each end of said frame 1, said worms 34 being driven by suitable bevel gears 36 and a shaft 37 provided with a spur gear 38 driven by the pinion 39 of a suitable motor 41.

On the inner side of each end of said upper housing 33 is a link 43 pivotally suspended from a sleeve 44 slidable upon a square shaft 46 rigidly secured to said upper housing 33. The lower end of the link 43 is provided with a pin 47 arranged to engage the slot 27 of the rigid arm 26 secured to the upper half 14. But the pin 47 is normally prevented from engaging said slot, while 75 the upper housing 33 is lowered to enclose the

upper half 14, by means of a spring 48 interposed between the inner top of said upper housing 33 and the top of the sleeve 44, the tension of which spring also normally retains said pin 47 between a pair of keepers 49, rigidly mounted upon a lower housing 51, which keep the pin directly opposite the slot 27 of the arm 26, as disclosed in Fig. 2 of the drawings.

A spring 51 normally holds the link 43 substantially vertical by pulling it against a flat limiting stop 52, shown in Figs. 3, 4, and 5 of the drawings, but removed from Fig. 2 with the end of the upper housing nearest the observer, as it would otherwise cover other parts and tend to confuse the said Fig. 2. The link 43 is free to slide vertically 15 over this stop 52 without changing its vertical position.

A pin 56 projects inwardly from the bottom edge of each end of the upper housing 33 to engage the slot 22 of the locking arm 21, actuate 20 the same to unlock and then disengage it, when moving to uncover the upper half 14, and to perform the reverse to lock and disengage it during a closing or covering movement of the said upper housing 33. 25

A lower housing 57 is also mounted for vertical movement to enclose and uncover the lower half 12 by means of suitable worms 58 driven through bevel gears 59, shaft 61, spur gear 62 and pinion 63 of a suitable motor 64. The lower 30 housing 57 is provided with a pair of grooved supporting cams 66 extending vertically from one side thereof to engage a pair of pins 67, one on each end of the upper half 14, when the same is moved to semi-loading position herein- 35 after described.

In operation:

The parts, during the washing or cleansing period, are in the position disclosed in Figs. 1, 2, and 3 of the drawings. That is to say, the upper and lower halves 14 and 12 are locked by the latch 18 in matching relation to form a cylinder and are enclosed by the upper and lower housings 33 and 57 respectively. The lower housing is adapted to contain a cleansing solution 71, as disclosed in Fig. 5 only. As the upper and lower halves are rotated by the cradle 3, trunnions 2 and pulleys 4 in the well known manner, the pins 47 and 56 of the upper housing 33 are beyond the path of rotation with the respective parts they later engage and actuate. 45

When the washing period is completed and the rotative power, not shown, is disconnected from the trunnion 2 of the cradle 3, the said cradle will normally come to rest with the several parts in their proper receptive positions by reason of the fact that the supporting cradle 3 is suspended below the axis of its trunnions 2 and the weight of the rigid arms 26, the levers 28 and links 29, all extending below the axis of said 60 trunnions 2, further tend to bring the matching upper and lower halves 14 and 12 and their levers and arms into the proper horizontal position to be engaged. When this position is attained, the pin 47 is placed through the aperture 8 of 65 the bracket 9 upon the frame 1 and the then registering aperture 7 of the wheel 6 upon the trunnion 2, as disclosed in Fig. 1 of the drawings. The insertion of this pin 47 will prevent rotation of the cradle 3 and its operating arms, links 70 and levers, and hold the same in proper receptive position.

The motor 41 is started, which rotates the worms 34 and raises the upper housing 33 to uncover the upper half 14 of the cylindrical 75

washer. The first or initial portion of this upward movement first moves the pin 56 into the slot 22 of the arm 21 (see Fig. 2 of the drawings) and after engaging said slot moves said arm to release the latch 18 from the free edge of the upper half 14. The pin 47 of the link 43 is prevented from engaging the slot 27 in the lower end of the rigid arm 26 attached to the upper half 14, by the tension of the spring 48 on the sleeve 44 from which the link 43 is suspended, until the pin 56 has actuated the arm 21 to release or unlock the latch 18 and thereby release the free edge of the upper half 14. After the pin 56 has disengaged the slot 22 of the arm 21 in its continued upward movement, and when the sleeve 44 reaches its lowermost position on the square rod 46, the pin 47 will be moved from between the keepers 49 and into the vertical slot 27 on the lower end of the rigid arm 26 attached to the upper half 14, as disclosed in Fig. 2 of the drawings. The upper housing 33 then continues to move upwardly and by means of the pin 47 moves the upper half 14 of the cylindrical washer to what I term a semi-loading or upright position, with the pins 67 of the said upper half 14 resting against the supporting cams 66 of the lower housing, as disclosed in Fig. 4 of the drawings. The upward movement of the housing 33 is stopped at this point by means of any suitable mechanism, not shown, as it forms no part of the present invention and is subject to unlimited variation.

The motor 64 is now started, which lowers the lower housing 57 to uncover the lower half 12 of the washer. As the lower housing 57 moves downwardly, the grooved supporting cams 66 move downwardly also, and the grooves 91 thereof engage the pins 67 and lower the upper half 14 until it engages the flange 31 of the lever 23 when said lever will be moved and through its connecting link 29 move the lower half 12 of the washer to a dumping position, as disclosed in Fig. 5 of the drawings. Any suitable truck 72 with a suitable apron 73 may be in readiness to receive the load thus automatically dumped from the lower half 12. At the same time a new load may be placed within the upper half 14 which has been inverted or moved to a loading position. When the new load has been placed within the upper half, while in the loading position, the motor 64 is reversed, which will return the lower half 12 to normal position, and the lower housing to enclose said lower half 12. But it should be noted that the lower half 12 is fully restored to its matching or normal position before the upper half 14 is fully returned to semi-loading position. The purpose of this is to have the lower half 12 in receiving position before the upper half 14 actually dumps its new load into the waiting lower half 12.

When the upper half 14 is nearing its semi-loading position, the now horizontal slot 27 in the free end of the rigid arm 26 will engage the pin 47, but if said pin should not accurately register with the slot 27, the lower end of the link 43 will be moved against the tension of the spring 51 until the pin 47 thereon registers with, and snaps into, the now horizontally disposed slot 27.

The motor 64 is then stopped and the motor 41 reversed, and the upper housing 33 is lowered and the pin 47, aided by the tension of the spring 48 on the sleeve 44, moves the rigid arm 26 and upper half 14 downwardly until said upper half is

closed upon the lower half 12, at which time the pin 47 of the link 43 will continue to move downwardly and out of the now vertical slot 27 and into the space between the keepers 49. Continued downward movement of the upper housing 33 will cause the pin 56 to enter the slot 22 of the now upwardly extending or unlocked locking mechanism and move the same to lock the latch 18 and secure the upper and lower halves 14 and 12 into matching relation to form the 10 cylinder.

As the pins 56 and 47 have disengaged their respective slots, the cradle 3 with its upper and lower halves is free to rotate and wash in the usual manner.

Having described my invention, I claim:

1. An automatic loading and dumping washer comprising the combination of a perforated horizontally disposed cylinder rotatably suspended and split longitudinally and axially into upper 20 and lower halves; an upper housing mounted for vertical movement to enclose and uncover the upper half of said cylinder; a lower housing also mounted for vertical movement to enclose and uncover the lower half of said cylinder and 25 adapted to contain a cleansing solution; means connected to the upper housing for moving the upper half of the cylinder to a semi-loading position when said upper housing is moved to uncover said upper half; means connected to the lower 30 housing for moving the upper half to full loading position when said lower housing is moved to uncover said lower half; and means actuated by the movement of said upper half from semi- to 35 full loading position to move the lower half of the cylinder to dumping position.

2. An automatic loading and dumping washer comprising the combination of a perforated horizontally disposed cylinder rotatably suspended and split longitudinally and axially into upper 40 and lower halves; an upper housing mounted for vertical movement to enclose and uncover the upper half of said cylinder; a lower housing also mounted for vertical movement to enclose and uncover the lower half of said cylinder and 45 adapted to contain a cleansing solution; means connected to the upper housing for moving the upper half of the cylinder to a semi-loading position when said upper housing is moved to uncover said upper half; means connected to the lower 50 housing for moving the upper half to full loading position when said lower housing is moved to uncover said lower half; and means actuated by the movement of said upper half from semi- to 55 full loading position to move the lower half of the cylinder to dumping position; and means for preventing rotation of said cylinder while the upper and lower halves thereof are being moved.

3. An automatic loading and dumping washer comprising the combination of a perforated horizontally disposed cylinder mounted for rotation and consisting of upper and lower halves hingedly connected to form said cylinder; means for locking said halves together; an upper housing mounted for vertical movement to enclose and uncover the upper half of said cylinder; a lower housing matching with the upper housing and also mounted for vertical movement to enclose and uncover the lower half of said cylinder and 60 adapted to contain a cleansing solution; means mounted upon the upper housing for engaging and releasing the cylinder locking means during the initial portion of the movement of said upper housing to uncover said upper half; means con- 65 70 75

nected to the upper housing for engaging and moving said upper half to a semi-loading position when said upper housing is moved to uncover said upper half; means connected to the 5 lower housing for engaging and moving the upper half of the cylinder from semi- to full loading position when said housing is moved to uncover said lower half; and means connected to said upper and lower halves of said cylinder and 10 actuated by the movement of said upper half from semi- to full loading position to move said lower half to a dumping position.

4. An automatic loading and dumping washer comprising the combination of a perforated horizontally disposed cylinder mounted for rotation and consisting of upper and lower halves hingedly connected to form said cylinder; means for locking said halves together; an upper housing mounted for vertical movement to enclose and 15 uncover the upper half of said cylinder; a lower housing matching with the upper housing and also mounted for vertical movement to enclose and uncover the lower half of said cylinder and adapted to contain a cleansing solution; means 20 mounted upon the upper housing for engaging and releasing the cylinder locking means during the initial portion of the movement of said upper housing to uncover said upper half; means connected to the upper housing for engaging and 25 moving said upper half to a semi-loading position when said upper housing is moved to uncover said upper half; means connected to the lower housing for engaging and moving the upper half of the cylinder from semi- to full loading 30 position when said housing is moved to uncover said lower half; means connected to said upper and lower halves of said cylinder and actuated by the movement of said upper half from semi- to full loading position to move said lower 35 half to a dumping position; and means for preventing rotation of the cylinder while the upper and lower halves thereof are being moved.

5. An automatic loading and dumping washer comprising the combination of a perforated, horizontally disposed, cylinder rotatably suspended and consisting of hingedly connected upper and 40 lower halves; an upper housing mounted for vertical movement to enclose and uncover said upper half of said cylinder; a lower housing also 45 mounted for vertical movement to enclose and uncover the lower half of said cylinder and matching with said upper housing and adapted to contain a cleansing solution; means connected to the upper housing for engaging and moving the upper half to a semi-loading position when said upper housing is moved to uncover said upper half and to move said upper half from semi-loading 50 to closed position upon the lower half of said cylinder and to disengage said upper half when said upper housing is moved to enclose said upper half whereby said upper half may be free to rotate; means mounted upon the lower housing for engaging the said upper half and for moving the same from semi- to full loading position when 55 said lower housing is moved to uncover said lower half of the cylinder and for moving said upper half from full loading to semi-loading position and into engaging relation with the moving means of the upper housing when said lower housing is moved to enclose the lower half of the cylinder; and means connected to the lower half of the cylinder and actuated by the movement of the upper half from semi- to full loading position to move 60 said lower half to dumping position and for mov- 65

ing said lower half from dumping to cylinder forming position with said upper half when said upper half is returned to semi-loading position when said lower housing is moved to enclose said lower half.

6. An automatic loading and dumping washer comprising the combination of a perforated, horizontally disposed cylinder rotatably suspended and consisting of hingedly connected upper and lower halves; an upper housing mounted for vertical movement to enclose and uncover said upper half of said cylinder; a lower housing also mounted for vertical movement to enclose and uncover the lower half of said cylinder and matching with said upper housing and adapted to contain a 10 cleansing solution; means connected to the upper housing for engaging and moving the upper half to a semi-loading position when said upper housing is moved to uncover said upper half and to move said upper half from semi-loading to closed 15 position upon the lower half of said cylinder and to disengage said upper half when said upper housing is moved to enclose said upper half whereby said upper half may be free to rotate; means mounted upon the lower housing for engaging the said upper half and for moving the same from semi- to full loading position when said lower housing is moved to uncover said lower half of the cylinder and for moving said upper half from full loading to semi-loading position and into engaging relation with the moving means of the upper housing when said lower housing is moved to enclose the lower half of the cylinder; means connected to the lower half of the cylinder and actuated by the movement of the upper half from semi- to full loading position to remove said lower half to dumping position and for moving said lower half from dumping to cylinder forming position with said upper half when said upper half is returned to semi-loading position when said lower housing is moved to enclose said lower half; and locking means actuated by the uncovering and enclosing movement of the upper housing to unlock and lock, respectively, said upper and lower halves.

7. An automatic loading and dumping washer comprising the combination of a perforated, horizontally disposed, cylinder rotatably suspended and consisting of hingedly connected upper and lower halves; an upper housing mounted for vertical movement to enclose and uncover said upper half of said cylinder; a lower housing also mounted for vertical movement to enclose and uncover the lower half of said cylinder and matching with said upper housing and adapted to contain a cleansing solution; means connected to the upper housing for engaging and moving the upper half to a semi-loading position when said upper housing is moved to uncover said upper half and to move said upper half from semi-loading to closed position upon the lower half of said cylinder and to disengage said upper half when said upper housing is moved to enclose said upper half whereby said upper half may be free to rotate; means mounted upon the lower housing for engaging the said upper half and for moving the same from semi- to full loading position when said lower housing is moved to uncover said lower half of the cylinder and for moving said upper half from full loading to semi-loading position and into engaging relation with the moving means of the upper housing when said lower housing is moved to enclose the lower half of the cylinder; means connected to the lower half of the cylinder and actuated by the movement of the upper half from semi- to full loading position to move said lower half to dumping position and for mov- 70

- the cylinder and actuated by the movement of the upper half from semi- to full loading position to move said lower half to dumping position and for moving said lower half from dumping to 5 cylinder forming position with said upper half when said upper half is returned to semi-loading position when said lower housing is moved to enclose said lower half; locking means actuated by the uncovering and enclosing movement of 10 the upper housing to unlock and lock, respectively, said upper and lower halves; actuating means for said locking means mounted on the upper housing; and means for normally retaining the cylinder with the lower half lowermost, and the 15 upper half uppermost, to facilitate engaging relation of the moving and lock-actuating means connected to the upper housing with said locking and moving means.
8. An automatic loading and dumping washer 20 comprising an open rectangular cradle; a supporting frame; trunnions mounted upon the upper surface and at each end of said cradle and rotatably mounted within said frame, to rotatably suspend the cradle; a perforated cylinder comprising upper and lower halves hingedly mounted upon opposite sides of said cradle; an upper housing mounted for vertical movement on said frame to enclose and uncover the upper half of said cylinder; a rigid arm depending 25 from each end of the upper half and extending beyond the cradle and having a slot in the lower end thereof; a link pivotally suspended from each inner end of the upper housing and having a pin on the lower end thereof to releasably engage the slot in the rigid arm and raise the upper half to a semi-loading position when said housing is 30 moved to uncover said upper half; a lower housing also mounted for vertical movement on the frame to enclose and uncover the lower half of said cylinder and adapted to contain a cleansing solution; a pair of cam supports mounted 35 upon the lower housing for releasably engaging the upper half or the cylinder when in semi-loading position and for lowering the said upper half to full loading position when said lower housing is moved to uncover the lower half of 40 the cylinder and for returning said upper half to semi-loading position and the slotted arms thereon into engaging relation with the links depending from the upper housing when said lower housing is moved to cover the lower half of said cylinder; a lever pivotally connected to the cradle concentric with the hinge of the upper half and having one free end depending inside of the cradle and having a flange on its opposite end arranged to releasably engage the upper half 45 during a portion of its movement from semi-loading to full loading position; links connecting the first end of each lever with the lower half of the cylinder to move said lower half to a dumping position when the upper half is moved to full 50 loading position and to return said lower half to normal matching position with the upper half before said upper half is returned to semi-loading position by an enclosing movement of the lower housing; and means for moving the upper 55 and lower housings independently of each other.
10. An automatic loading and dumping washer comprising an open rectangular cradle; a supporting frame; trunnions mounted upon the upper surface of each end of the cradle and rotatably 45 mounted within said frame to rotatably suspend said cradle in a horizontal position; a perforated cylinder comprising matching upper and lower halves each having one side hingedly connected to opposite sides of said cradle and their free 50 sides resting upon opposite sides of said cradle; locking means mounted upon the cradle for releasably engaging the free side of the upper half when matching with the lower half in the cradle to form a cylinder and lock said halves in matching relation upon said cradle; a rigid arm having a slot in the free end thereof connected to each end of said upper half and depending beyond said cradle; an upper housing mounted for vertical movement on said frame to enclose and uncover 60 said upper half of the cylinder; a lug projecting from each end of said upper housing to engage, actuate, then disengage the locking mechanism on the cradle to unlock the said halves during the initial movement of said upper housing to 65 uncover said upper half and to engage, actuate and disengage said locking mechanism during the last portion of the movement of said upper housing to enclose said upper half, to lock said halves in matching relation; a link pivotally suspended 70 from each inner end of said upper housing and having a lug on the lower end thereof to releasably engage the slot in its respective rigid arm depending from the upper half of the cylinder, when the upper housing is moved to uncover said 75

upper half, and to move said upper half to a semi-loading position; a lower housing also mounted for vertical movement on said frame to enclose and uncover the lower half of the cylinder and adapted to contain a cleansing solution; a pair of cam supports mounted upon said lower housing for releasably engaging the upper half of the cylinder when in semi-loading position to release the rigid arms from engaging relation with the links on the upper housing and to lower said upper half to loading position when said lower housing is moved to uncover said lower half, and for returning said upper half to semi-loading position when said lower housing is moved to cover said lower half of the cylinder; and means connected to the lower half of the cylinder and actuated by the upper half during the latter portion of the movement of said upper half from semi- to loading position to move the lower half to dumping position, and to move said lower half from dumping to normal matching position during the first portion of the movement of said upper half from loading to semi-loading position whereby said lower half may be in position to receive a load from the upper half before said upper half reaches semi-loading position, when said lower housing is moved to cover said lower half of the cylinder.

11. An automatic loading and dumping washer comprising the combination of a perforated horizontally disposed cylinder rotatably suspended and split longitudinally and axially into upper and lower hingedly connected halves; an upper housing mounted for vertical movement to enclose and uncover the upper half of said cylinder; means mounted upon the upper housing and disengaged from said upper half and moved, by a movement of said upper housing, to uncover said upper half, to engage said upper half and move the same to a semi-loading position; a lower housing also mounted for vertical movement to enclose and uncover the lower half of said cylinder and matching with said upper housing to fully enclose said cylinder, said lower housing being adapted to contain a cleansing solution; means connected to said lower housing and disconnected from said upper half and moved by said lower housing, when moved to uncover said lower half, to disengage said upper half from engaging relation with said upper housing and to move said upper half from semi- to full loading position and to return said upper half into operative engaging relation with the moving means connected to the upper housing when said lower housing is moved to cover said lower half; and means connected to said lower half and actuated

by movement of the upper half from semi-loading to full loading position to move said lower half to dumping position and to return said lower half to a load receiving position by movement of the upper half from loading to semi-loading position, when the lower housing is moved to cover said lower half. 5

12. An automatic loading and dumping washer comprising the combination of a perforated horizontally disposed cylinder rotatably suspended and split longitudinally and axially into upper and lower hingedly connected halves; an upper housing mounted for vertical movement to enclose and uncover the upper half of said cylinder; means mounted upon the upper housing and disengaged from said upper half and moved, by a movement of said upper housing to uncover said upper half, to engage said upper half and move the same to a semi-loading position; a lower housing also mounted for vertical movement to enclose and uncover the lower half of said cylinder and matching with said upper housing to fully enclose said cylinder, said lower housing being adapted to contain a cleansing solution; means connected to said lower housing and disconnected from said upper half and moved by said lower housing, when moved to uncover said lower half, to disengage said upper half from engaging relation with said upper housing and to move said upper half from semi- to full loading position and to return said upper half into operative engaging relation with the moving means connected to the upper housing when said lower housing is moved to cover said lower half; means connected to said lower half and actuated by movement of the upper half from semi-loading to full loading position to move said lower half to dumping position and to return said lower half to a load receiving position by movement of the upper half from loading to semi-loading position, when the lower housing is moved to cover said lower half; means for locking the upper and lower halves of the cylinder into matching, cylinder forming, relation; and means, actuated by the initial movement of the upper housing to uncover the upper half, to engage, actuate to unlock and then disengage said locking means, and to engage, actuate to lock and then disengage said locking means during the last portion of the movement of the upper housing to cover said upper half of the cylinder, whereby said cylinder may be free to rotate within the matched housings and in disengaging relation with the actuating means for moving said upper and lower halves. 50
